[57] CLAIM

The ornamental design for a liquid crystal display, as shown and described.

DESCRIPTION

FIG. 1 is a front elevational view of a liquid crystal display showing my new design;

FIG. 2 is a rear elevational view thereof;

FIG. 3 is a top plan view thereof, with the bottom being a mirror image;

FIG. 4 is a side elevational view thereof, with the opposite side being a mirror image;

FIG. 5 is a sectional view taken along line 5—5 in FIG. 1;

FIG. 6 is a front elevational view thereof, with the emblems shown in an energized form; and,

FIG. 7 is a perspective view thereof, with the broken line showing for illustrative purposes only and forming no part of the claimed design.
